H. H. LOCKWOOD.
TWO WHEELED VEHICLE.

No. 450,166.

Patented Apr. 14, 1891.

UNITED STATES PATENT OFFICE.

HENRY H. LOCKWOOD, OF OLEAN, NEW YORK.

TWO-WHEELED VEHICLE.

SPECIFICATION forming part of Letters Patent No. 450,166, dated April 14, 1891.

Application filed February 18, 1890. Serial No. 340,841. (No model.)

To all whom it may concern:

Be it known that I, HENRY H. LOCKWOOD, a citizen of the United States, residing at Olean, in the county of Cattaraugus and State of New York, have invented certain new and useful Improvements in Wheeled Vehicles; and I do hereby declare the following to be a full, clear, and exact description of the invention, such as will enable others skilled in the art to 5 which it appertains to make and use the same.

This invention relates to certain improvements in vehicles, which will be hereinafter more particularly described and pointed out.

In the accompanying drawings, forming 15 part of this specification, Figure 1 is a side elevation of a vehicle with the improvements attached. Fig. 2 is a top or plan view of one-half of the running-gear. Fig. 3 is an elevation of one-half of the axle and springs, &c. 20 Figs. 4, 5, 6, 7, 8, and 9 are details enlarged.

A represents the seat of the vehicle, and A' the seat-riser.

B is the shaft, B' the circle bar, and B'' the back bar.

25 C is the pole, which is constructed as follows: A solid piece of suitable timber is sawed along the lines c c c, &c., and c' c'' c'', &c., from the end C'' to C', thus forming three strips of equal dimensions. Three or more 30 separate pieces may be thus combined. The middle strip C'' is intended to pass through the mortises in the bars B' B'', forming a tenon to each bar, and the outside pieces D D will pass over the bars B' B'', and the three or 35 more strips will be secured at the two ends by screw-bolts d in the usual manner to make the end parts solid. The strips will be held apart by spools e e, &c., through which and the strips will pass screw-bolts d' d', &c., 40 as shown in Fig. 1. This method will form a substantial trussed pole much lighter and stronger than when of solid material.

45 E E are the foot-rest bars, designed to be readily detachable by means of the following devices, which are in detail enlarged in Figs. 6, 7, 8, and 9.

F is the spring-bar.

G is the spring.

50 Under the spring-bar F at each end is a hanger F'. (Shown in Fig. 5.) In this hanger is a socket f (shown in dotted lines) for the

reception of the hooks e e on the upper ends of the foot-rest bars E E. The other ends of the bars E E have hooks e' e', which engage the staples e'' e'' under the back bar B''. 55

f' is a button pivoted to the hanger, so that when the foot-bars E are in place the button f' will prevent the end e from jumping out of the socket or mortise f.

When it is desired to remove the foot-rest, 60 by turning the buttons f' the hooks e can be lifted out and the foot-rest dropped down, and the other ends e' can be easily detached from the staples e''.

When the vehicle is wide, a middle foot-rest bar will be required. E', Fig. 6, represents such a middle bar, which has at one end a hook e, similar to the outside foot-rest bars E, which drops into a socket f in a hanger which is cast upon the plate of the middle clip-holder G', Fig. 8. This middle foot-rest bar E' extends under the foot-rest slats about 70 one-third of the distance only.

In Figs. 3 and 4 is represented the method of suspending the ends of the spring G. H is 75 a standard, having on its end a ball h. This standard is forged onto the shaft-rim I, as seen in Fig. 1. A spring-stirrup is formed of two similar parts J J', having at their upper ends concavities h' to fit over the ball h, so that 80 when bolted together, the whole will form a ball-and-socket or universal joint. To the lower end of the spring-stirrup J J' is attached the end of the spring G in the usual manner.

In Fig. 9 is represented a device to deaden 85 the spring. K is a wheel-axle. On the middle clip K' of the axle is a projection having a hole k, which is in line longitudinally with the center bolt g, of the spring G. k' is a short brace fitted at its lower end to enter the 90 hole k in the clip-plate K', and has a shoulder k² to prevent it from dropping. Its upper end is curved so that it will come directly under the spring-clip L, and in the end of K' is a hole l, to receive the lower end of the spring-bolt g. When it is desirable to deaden the 95 spring, the brace k' is to be inserted in the hole k, and the bolt g is to be inserted in the hole l, when the spring will be sustained by the brace.

I am made aware that a two-wheeled vehicle has been provided with a foot-rest de-

tachably connected thereto, such foot-rest being secured by nuts which have to be taken off when the foot-rest is to be removed.

In my device I use pivoted catches which are simply turned and are not removed from the vehicle, and hence are in no danger of being lost.

What I claim is—

1. The combination of a two-wheeled vehicle with a removable foot-rest detachably connected at both ends with the vehicle and pivoted catches at one end, whereby the foot-rest is held from accidental displacement and may be removed by turning the catches and without removing them from the vehicle, as set forth.

2. The combination, of the spring-bar F,

the hangers F', secured thereto and having the socket f, the buttons f', the bars E, having the hooks e and e', and the back bar B'', having the staples e'', as set forth.

3. The combination of the axle K, having at its middle the clip K', with the hole k, the brace k', fitting said hole and having the shoulder k², and the spring G and its spring-clip L, the said brace coming under this clip, as set forth.

In testimony whereof I affix my signature in presence of two witnesses.

HENRY H. LOCKWOOD.
